HARRY L. BEACH, OF COSHOCOTON, OHIO.

DESIGN FOR A DISPLAY CASE.

Application filed March 2, 1921. Serial No. 449,231. Term of patent 3½ years.

To all whom it may concern:

Be it known that I, HARRY L. BEACH, a citizen of the United States, residing at Coshocton, in the county of Coshocton and State of Ohio, have invented a new, original, and ornamental Design for a Display Case, of which the following is a specification, reference being had to the accompanying drawing, forming part thereof.

The single figure is a perspective view of a display case embodying my new design.

The drawing shows a rectangular box A having three of its sides B provided with an

opaque panel C and a transparent panel D, a shelf E being supported within the case at or about the junction of the two panels. The separate doors F, G, provide communication with the interior of the case both above and below the shelf E.

I claim:

The ornamental design for a display case, substantially as shown and described.

In testimony that I claim the foregoing as my own, I have hereto affixed my signature.

HARRY L. BEACH.
